United States Patent Office.

ANDREW HARRIS, OF PHILADELPHIA, PENNSYLVANIA.

Letters Patent No. 98,162, dated December 21, 1869.

HYDRO-PNEUMATIC GOVERNOR.

The Schedule referred to in these Letters Patent and making part of the same.

I, ANDREW HARRIS, of Philadelphia, county of Philadelphia, State of Pennsylvania, have invented a Hydro-Pneumatic Governor for steam-engines, of which the following is a specification.

Nature and Object of the Invention.

My invention consists of a vessel containing two compartments, communicating with each other, and partly filled with water, or other suitable fluid, in combination with an exhausting or blowing-apparatus, which is operated by the engine, and by which, in conjunction with an inlet or outlet-cock or tube, the air is caused to so act on the water, that the latter becomes a medium for operating the throttle-valve of a steam-engine, all of which is fully described hereafter.

Description of the Accompanying Drawing.

Figure 1 is a vertical section of my improved regulator for steam-engines, and

Figure 2, a modification of the same.

General Description.

A is an outer casing, closed at the bottom, and connected at the top, by an annular plate, x, to an inner casing, B, the lower open end of which is situated at a short distance above the bottom of the outer casing, so that there may be a free communication between the chamber D of the inner casing and the annular chamber E, between the two casings.

Water, or other suitable fluid, is poured into the chambers, until they are about half full; and the inner chamber D contains a suitable float, m, connected by a rod, a, to one arm of a lever, G.

Thus far, my invention is similar to part of the regulating-apparatus for exhausters of gas-works, for which Letters Patent were granted to Joseph A. Harris on the 26th day of March, 1867; but in adapting the above device to a steam-engine, with the view of regulating the speed of the same, I use an exhausting-apparatus, driven by the engine, the exhausting-apparatus consisting, in the present instance, of a simple rotary pump, H, the pulley of the pump being driven directly or indirectly from the crank-shaft, or other rotating part of the engine, and the exhaust-pipe n of the pump communicating with the interior of the circular chamber E, at or near the top of the same.

A tube or cock, q, situated near the top of the casing, admits air to the said annular space E.

The outer arm of the lever G is connected, by any suitable appliances, to the throttle-valve of a steam-engine.

As the exhaust-pump derives its motion, either directly or indirectly, from the steam-engine, the exhaustion of the chamber E will be commensurate with the speed of the engine. Thus, if the speed of the engine be excessive, the air will be exhausted from the chamber E faster than air can pass through the pipe or cock q to take its place. The result of this must be the rising of the water in the said chamber E, the corresponding lowering of the water in the chamber D, the descent of the float, and the closing of the throttle-valve to an extent which will insure a proper reduction in the speed of the engine.

If, on the contrary, the speed of the engine diminishes, the water in the chamber D will rise, owing to the supply of air, through the cock q, to the annular channel, being greater than the amount of air exhausted therefrom, and the consequence will be the opening of the throttle-valve, and an increased speed of the engine.

It will now be seen, that the movement of the throttle-valve is effected directly through the agency of water, the movement of the latter being effected through the agency of air, and the latter being under the control of the engine; hence, I have entitled my invention a hydro-pneumatic regulator for steam-engines.

This regulator, I have found, by repeated experiments, to be most uniform and sensitive in its action.

Hitherto I have referred to the exhaustion of air from the annular chambers, and to the pipe or cock q as an inlet; but it will be evident, that by reversing this arrangement, namely, by causing the pump to force air into the chamber, and permitting the air to escape therefrom through the cock q, the engine can be made to so control the water, through the medium of the air, as to operate the float, and, consequently, the throttle-valve, with results the same as those described above.

It should here be understood that I do not desire to confine myself to a rotary pump, for exhausting air from, or forcing air into the annular chamber, as any other blowing or exhausting-apparatus will serve the purpose, providing it be operated by, and uniformly with the engine.

Nor is it essential that the air and water-chambers should be arranged precisely as shown in fig. 1; the casing, for instance, may consist of a simple square box, A', as shown in fig. 2, a partition, a', extending from the top nearly to the bottom, the float being contained in one chamber, and air being admitted to and withdrawn from the other chamber, above the water; in fact, a variety of different arrangements of

chambers may be adopted, without departing from the main feature of my invention.

Claim.

A vessel, containing two compartments, communicating with each other, substantially as described, and partly filled with water, or other suitable fluid, in combination with an exhausting or blowing-apparatus, which is driven by the engine, and by which, in conjunction with an inlet or outlet-cock or tube, the air

is caused to so act on the water, that the latter becomes a medium for operating the throttle-valve of the engine.

In testimony whereof, I have signed my name to this specification, in the presence of two subscribing witnesses.

ANDREW HARRIS.
